UNITED STATES PATENT OFFICE.

JOHN F. HARRISON, OF MILWAUKEE, WISCONSIN, ASSIGNOR TO ALLIS-CHALMERS COMPANY, OF MILWAUKEE, WISCONSIN, A CORPORATION OF NEW JERSEY.

CUSHIONING DEVICE FOR FREELY-GYRATING MECHANISMS.

No. 822,893.

Specification of Letters Patent.

Patented June 5, 1906.

Application filed January 14, 1904. Serial No. 188,977.

To all whom it may concern:

Be it known that I, JOHN F. HARRISON, a citizen of the United States, residing at Milwaukee, in the county of Milwaukee and State of Wisconsin, have invented certain new and useful Improvements in Cushioning Devices for Freely-Gyrating Mechanism, of which the following is a specification.

My invention relates to a cushioning device for freely-gyrating mechanism.

The device is to be used in the practical application of the mechanical movement described and claimed in the patent to W. W. Beaumont, No. 526,213, dated September 18, 1894, to avoid the difficulties encountered in starting and stopping, as will be hereinafter more specifically set forth.

In the drawings, Figure 1 shows the said mechanical movement applied to a suspended flour-bolter, together with the cushioning device and related parts of my invention. Fig. 2 shows a plan view of the cushioning device and a section of the arresting-pin on the line *x x*. Figs. 3 and 4 show a modification 25 of the cushioning device.

The lower part of the bolter is shown at 1. This bolter is suspended by freely-movable rods 2 2, provided with hooks passing through eyelets 3 3, firmly attached to fixed side rods 30 4 4, parallel with the vertical axis of the bolter and attached to a bottom plate 41 and a similar top plate. (Not shown.) The suspension may be made in any other way permitting free movement of gyration in a horizontal plane—such as, for instance, by so-called “reeds” or “flexible wooden strips” directly attached to the bolter and the part from which it is hung. The shaft 5, freely rotating in upper and lower bearings in the bolter, 35 carries an eccentrically-mounted weight 6 on its lower end, as shown, and also on its upper end. This weight may be provided with small removable weights, as shown, in order to vary it. The shaft is rotated from a vertical shaft mounted in a fixed bearing located 40 above its upper end by any of the well-known driving connections permitting of free movement of the shaft in a horizontal plane while rotating on a vertical axis, such as a connecting-shaft with two universal joints.

When the shaft 5, together with the weight

6, is rotated at a certain speed, this weight, while constantly changing its position with regard to the bolter, will by acting on its lever-arm impart to the bolter a constant 55 tendency to change its position in a direction which is exactly opposed to the direction of rotation of the weight, thus throwing it out to the other side of the neutral axis from the center of gravity of the weight. The amount 60 of this throw will vary with the proportion of the weight of the bolter to that of the rotating weight with the lever-arm of the latter and with the speed. By reason of this throwing out of the bolter, which throw is always in line with the radial direction of the weight, a gyroscopic motion around the neutral axis will be imparted to the bolter. With a constant proportion between the weight of the bolter, the rotating weight, and the lever-arm of the latter a certain speed, called the 70 “critical speed of rotation,” exists, in which perfect balance is attained, and the parts will assume a position wherein the vertical axis of the bolter will remain parallel to the neutral 75 axis at a certain distance while gyrating around it. The amount of throw will be such that the moment of the mass of the bolter into the distance of its axis from the neutral axis will be equal and opposite to the moment of the weight into its distance from the center of gravity to the axis of the shaft, the two moments thus neutralizing each other. At a lower speed the parts will gyrate on a 80 conical surface around the center of suspension of the shaft. At a higher speed this conical surface will be inverted.

It will be understood that the two weights, one at each end of the shaft, act as one of double the weight, and are thus arranged in 90 order to balance the strain on the shaft.

When starting the mechanism, the influence of centrifugal force will act, through the weight, to throw the latter and the attached parts violently outward in the direction of 95 the weight, producing irregular swinging motion. This will continue until the critical speed has been reached and the parts are in balance. The same action will occur in stopping and may occur during the operation of 100 the machine, if for any reason the speed does not remain constant. My device has been

designed in order to take care of this irregular motion, which strains the parts unduly and may cause the bolter to swing out sufficiently to interfere with adjoining apparatus 5 and to damage attached parts.

As shown in the drawings, an eccentric pin 7 is provided on the shaft, its eccentricity with regard to the axis of the shaft being equal to the desired throw. The outer side 10 of this pin is in contact with the inner coil of a coil-spring 8 when the mechanism is at rest and is located on the side toward the weight, as shown in Fig. 1. The outer end of the coil-spring is attached to the inner wall of an 15 annular flanged ring 9, which is firmly bolted to the floor. When the machinery is started, the pin works against the resistance of the spring, which prevents the parts from flying out too far and acts as a cushion, avoiding 20 jar and breakage of the parts. As soon as the critical speed has been attained the pin will no longer contact with the side of the spring, but its axis will be coincident with the neutral axis—that is to say, the axis of the 25 bolter when the parts are at rest and around which it gyrates. Upon slowing down or stopping, the spring-cushion will again come into action, the parts finally coming to rest in the full-line position.

30 Figs. 3 and 4 show a modification in which three spiral springs 10 are adjustably attached at equal angles to each other by means of eyebolts to floor-brackets 11. The inner ends of these springs are attached to a 35 plate 12, having an opening in its center whose radius is equal to the throw plus half the diameter of the pin. The action of this device is precisely similar to that of the one previously described. The shaft and pin are 40 shown in the position which they assume after equilibrium has been attained.

It is evident that the springs may be arranged in a different manner.

It will be understood that while the device is shown applied to a flour-bolter it is 45 equally applicable to any other machines in which a gyrating movement is produced by the rotation of an unbalanced weight, such as coal-screens, sieves, &c.

50 Having thus described my invention, what I claim as new, and desire to secure by Letters Patent, is—

1. A gyrating bolter comprising a sieve-box, means for freely supporting the sieve-box, and an independent elastic means normally spaced from the bolter for restricting the abnormal outward throw of the bolter during gyration.

60 2. In combination with a gyrating sieve-box, means for freely supporting the sieve-box for gyration, an eccentrically-weighted rotatable shaft mounted in the sieve-box, a pin on the shaft, an independent fixed cushioning means for the pin, said pin and cushion-

ioning means coacting to cushion the abnormal outward movement of the sieve-box in a radial direction. 65

3. In combination with a gyrating sieve-box, means for freely supporting the sieve-box for gyration, an eccentrically-weighted 70 rotatable shaft mounted in the sieve-box, a pin on the shaft, and a fixed elastic cushioning device provided with a central opening, the pin contacting with the inner wall of the opening during abnormal outward movement 75 of the sieve-box.

4. The combination of a gyrating sieve-box, means for freely supporting the sieve-box for gyration, an eccentrically-weighted 80 rotatable shaft mounted in the sieve-box, an eccentric pin on the shaft, and a fixed elastic cushioning device coacting with the pin.

5. The combination of a gyrating sieve-box, means for freely supporting the sieve-box for gyration, an eccentrically-weighted 85 rotatable shaft mounted in the sieve-box, an eccentric pin on the shaft located in the plane of the axis of the shaft and the center of gravity of the weight, and a fixed spring means provided with a central opening in 90 line with the axis of rotation and coacting with the pin.

6. The combination of a gyrating sieve-box, means for freely supporting the sieve-box for gyration, an eccentrically-weighted 95 rotatable shaft mounted in the sieve-box, an eccentric pin on the shaft, and a fixed coil-spring, the pin coacting with the spring.

7. The combination of a gyrating-bolter, rods for freely supporting the bolter for gyration, an eccentrically-weighted rotatable 100 shaft mounted in the bolter, a flexible driving connection for the shaft, an eccentric pin on the shaft, and a fixed cushioning-spring device provided with a central opening, the pin contacting with the wall of the central opening in 105 the spring when the bolter is at rest and rotating around its axis when the bolter is gyrating in equilibrium.

8. In a bolter, a sieve-carrying frame suspended to move freely laterally, an eccentrically-weighted vertical revoluble shaft mounted in the frame, independent fixed means for limiting the extent of the gyroscopic movement of the frame comprising a spring-stop secured to a fixed support and having a circular opening, and a pin on the shaft projecting into the opening. 110

9. The combination of a gyrating bolter, supporting means for the bolter preventing 115 rotation, and independent elastic means for restricting the abnormal outward throw of the bolter during gyration.

10. The combination of a gyrating bolter, means for preventing rotation of the bolter, 120 and independent elastic means for restricting the abnormal outward throw of the bolter during gyration. 125

11. In a bolter, a sieve-box freely supported for gyration, an eccentrically-weighted rotatable means mounted in the sieve-box, an eccentric means on the rotatable means, and means coacting with the eccentric means for restricting the abnormal outward throw of the bolter during gyration.
12. A gyrating bolter comprising a sieve-box, means for freely supporting the sieve-
- box, and a normally inoperative elastic means for restricting the abnormal outward throw of the bolter during gyration.
- In testimony whereof I affix my signature in presence of two witnesses.
